HEAT EXCHANGER

Wilbur H. Armacost, New York, N. Y., assignor to
The Air Preheater Corporation, New York,
N. Y.

Application November 25, 1938, Serial No. 242,363

1 Claim. (Cl. 257—216)

The present invention relates to improvements in heat exchangers and particularly to plate type exchangers in which a fluid to be heated, such as air, flows through passages extending in directions transverse to the flow of the heating gases which may be derived from a boiler.

In this type of heater the portions of the plates which are located nearest to the source of the heating gases frequently become oxidized and burnt due to the high temperatures to which they are subjected. An object of the present invention is to eliminate or at least reduce the oxidation and burning of these portions of the plate elements of the heat exchangers.

The invention will best be understood upon consideration of the following detailed description when read in conjunction with the accompanying drawing in which the single figure is a diagrammatic representation of a plate type heat exchanger embodying the invention.

In the drawing the numeral 10 designates a conduit through which gases flow in the direction indicated by the arrow from a furnace or the like to an outlet or stack. Interposed in this conduit are a pair of heat exchangers 11 and 12 arranged in series so that the gases flow first through the exchanger 11 and then through exchanger 12. The heat exchangers are of the well known plate type familiar to those skilled in the art and have passages alined with the conduit 10 for the flow of heating gases alternating with transversely extending passages for the flow of the fluid, such as air, that is to be heated.

The air to be heated initially enters the exchangers at 13 and passes from the outlet 14 of the exchanger 12 to the inlet 15 of the exchanger 11 through a duct 16 having walls 17 and 18 and located out of the path of the heating gases. Extending longitudinally or axially through the duct 16 is a partition 20 so arranged that the air passing over the parts of the exchanger 12 which are most remote from the source of heat in the direction of gas flow are directed to and pass over the portion 21 of the plates in the exchanger 11 which are nearest to the heat source in the direction of gas flow. The end of portion 21 of the partition 20 adjacent the exchanger 12 extends transversely across the air passages of this heater and is pivotally supported at 22 near this end so that air from an area of greater or less extent may be diverted from the relatively cool portion of the heater 12 through the subdivision 23 of duct 16 formed by the outer wall 17 and partition 20 to flow over the hottest portion 21 of the plates in the heater 11. As illustrated an additional partition 24 is provided in the duct 16 forming further passages 25 and 26 through which air from the relatively cooler portions of the exchanger 12

is directed to portions of the exchanger 11 which are subjected to cooler gases than pass over the most intensely heated section 21.

As a further means for reducing the cost of 5 economizers of this type, while at the same time affording protection against the hot gases encountered in service, the plates of the exchanger 12 may be made of carbon steel while the portions 21 of the plates of the exchanger 11 that are 10 subjected to the hottest gases may be made of a heat resistant alloy such as a steel including 18% chrome and 8% nickel while the more remote portions 24 of the plates of the exchanger 11 may be of 5% molybdenum steel alloy. The plates of 15 the exchanger 12 and the portions 27 of the plates in the exchanger 11 are shown corrugated while the most intensely heated portions 21 of the plates in the exchanger 11 are indicated as of plain construction, i. e. not corrugated.

20 It will be seen from the foregoing that in service the portions 21 of the plates in the exchanger 11 that are subjected to the hottest gases are protected by receiving air which has previously had its temperature increased the least because 25 of its passage through the portion of the exchanger 12 that is most remote from the source of heat in the direction of gas flow, i. e. by air which has been heated by transfer of heat from gases which have been cooled considerably in 30 passing over the plates in exchanger 11 and 12 that are nearer to the source of heat.

What I claim is:

In heat exchange apparatus; a conduit for the passage of heating gases; a pair of heat exchangers each having passages for the flow of a fluid to be heated, such as air, in a direction transverse to the flow of the heating gases, said exchangers being arranged in series in said conduit so that the heating gases flow through said exchangers in succession; a duct located out of the path of the heating gases and connecting the air outlet of one heat exchanger to the air inlet of the other heat exchanger so that the air passes through said exchangers in a direction generally counter to that of the heating gases; and a partition extending longitudinally of said duct and so located as to direct air from the portion of said one exchanger that is last contacted by said heating gases to the portion of said other exchanger that is first contacted by the heating gases; and means movably supporting the portion of said partition having an end edge adjacent and extending across the air passages at the outlet of 40 said one exchanger so that said partition portion may be moved to direct air through said duct from an area of larger or smaller extent at the air outlet of said one exchanger.

WILBUR H. ARMACOST.
